United States Patent Office

Des. 189,614
Patented Jan. 17, 1961

189,614

PUSHMOBILE

Dorr D. Beale, 5225 Duncraig Road, Minneapolis, Minn.

Filed Sept. 29, 1958, Ser. No. 52,791

Term of patent 14 years

(Cl. D14—3)

Fig. 1

Fig. 2

Fig. 1 is a front perspective view of a pushmobile showing my new design; and

Fig. 2 is a rear perspective view thereof.

I claim:

The ornamental design for a pushmobile, substantially as shown.
